CLAIM

The ornamental design for a glass with ornamental markings, as shown and described.

DESCRIPTION

FIG. 1 is a top, front perspective view of a glass with ornamental markings showing my new design; FIG. 2 is a front side elevational view thereof; FIG. 3 is a right side elevational view thereof; FIG. 4 is a rear elevational view thereof; FIG. 5 is left side elevational view thereof; FIG. 6 is a top elevational view thereof; and, FIG. 7 is a bottom elevational view thereof. The broken lines in the drawings depict portions of the glass with ornamental markings that form no part of the claimed design. The Dot-dash lines in the drawings represent the bounds of the claim and form no part of the claimed design. The hatching lines in the drawings are used to indicate contrast in appearance.
